UNITED STATES PATENT OFFICE.

HANSON THOMAS, OF PITTSBURGH, PENNSYLVANIA.

MACHINE FOR APPLYING NUTS TO BOLTS.

Application filed May 22, 1920. Serial No. 383,559.

To all whom it may concern:

Be it known that I, HANSON THOMAS, a citizen of the United States, and resident of Pittsburgh, in the county of Allegheny and State of Pennsylvania, have invented a new and useful Improvement in Machines for Applying Nuts to Bolts; and I do hereby declare the following to be a full, clear, and exact description thereof.

10 My invention relates to a machine for applying nuts to bolts.

The object of my invention is to provide a simple and efficient machine of this character in which the nuts are mechanically applied to the bolts, provision being made for automatically feeding the nuts to the bolts into position for application, whereby the nuts are quickly applied to the bolts without the employment of manual labor, thereby greatly increasing the output and doing away with the great amount of time and labor heretofore involved in this operation.

To these ends my invention comprises the novel features hereinafter set forth and 25 claimed.

In the drawings, Fig. 1 is a side elevation partly in section of my improved machine; Fig. 2 is a plan view partly in section; Fig. 3 is a section on the line 3—3, Fig. 2; 30 Fig. 4 is an enlarged sectional view of the carrier which is adapted to engage the nuts and deliver them to the nut holder; Fig. 5 is a longitudinal section of the nut holder; Fig. 6 is a front view of same; and Fig. 7 is 35 a detail of the nut-delivering mechanism.

In the drawings, the numeral 2 designates a suitable bed plate or base on which the parts composing my machine are mounted.

A shaft 3 is journaled in suitable bearings 4 in standards 5. A pulley 6 on the shaft 3 is connected up to any suitable source of power, although it is apparent that my machine may be driven directly by an electric motor, if desired.

45 Mounted on the shaft 3 is the spur-pinion 7 which meshes with the gear-wheel 8 mounted on the shaft 9 journaled in suitable bearings. A bevel-pinion 10 on the shaft 9 engages bevel-pinions 11 and 12 on the shaft 13. The pinion 11 is slidably keyed on the shaft 13 and is held in engagement with the bevel-pinion 10 by the spring 14 whereby stripping of the gears

is prevented in case of any obstruction to the rotation of the pinion 11 as more fully 55 hereinafter set forth.

Mounted on the shaft 13 is the cam 15 which engages the roller 16 mounted in the guide 17. The trunnions 18 of the roller 16 engage the slide-block 19 mounted in 60 the guide 17. The slide-block 19 has the downwardly extending portion 20 which is engaged by the fork 21 of the lever 32 pivotally mounted at 23 in the base 2.

The slide-block 19 has the threaded seat 65 25 formed therein to receive the threaded end of the nut-carrier 26. Within the carrier 26 is the pin member 27 slidable in said carrier, the transverse pin 28 connecting said pin 27 to the carrier 26, and a slot 29 70 being formed in said carrier to receive the pin. A spring 30 is interposed between the pin 27 and the inner end of the carrier 26, said spring normally acting to hold the pin 26 at the forward end of the slot 29 for 75 the purpose more fully hereinafter set forth.

The carrier 26 is preferably magnetized for the reason more fully hereinafter set forth.

The pin 27 normally projects beyond the 80 free end of the carrier 26 to engage the nut. The carrier 26 is slidable in the opening 31 in the frame 32. This frame 32 carries the nut-magazine 33 by which the nuts are fed one by one so as to be brought into register 85 with the opening 31. At the upper end of the magazine 33 is the hopper 34 into which the nuts are fed.

A shutter 34 is hinged to the nut magazine and normally acts to close the outlet of the 90 magazine when the carrier is in retracted position as shown in Fig. 1, a spring 37 being connected to said shutter and the frame 32 for holding the shutter closed.

Mounted in bearings 41 on the standard 39 95 is the sprocket 41. The sprocket 41 has the central bore 42 which forms a seat for the hollow nut-holder 43. This nut holder is composed of two parts inserted separately within the bore 43 of the sprocket and having a dove-tail connection 44 as clearly shown in Fig. 6. The lower section 45 of the nut-holder has a bore portion of three tapering faces 46 at its entrance, and the upper section 47 has a straight flat face 46^a with 100 a cam slot 48 formed therein. If a nut in

being advanced into the nut-holder by the carrier 26 should enter in the tapered portion of the holder in the position indicated in dotted lines Fig. 6, the upper corner of 5 the nut will project into the cam-slot 48, and by reason of the angular disposition of the slot the nut will be caused to rotate as it is advanced by the carrier, and the nut will be thrown around in position to enter the 10 square seat 49 in which it is held against rotation during the time the nut is being screwed on to the bolt.

The sprocket pinion 41 is connected up to the sprocket 50 on the shaft 3 by the sprocket-chain 51. The sprocket 50 is loosely mounted on the shaft 3 and is held between the plates 52 and 53, a spring 54 on the shaft 3 acting to hold the sprocket ordinarily in frictional driving relation with the plates 53, 20 but permitting of the slipping of the sprocket-wheel 50 in case of an obstruction to the movement of the said wheel.

Mounted on the guide 55 on the bed 2 is the slide 56 which carries the frame 57.

25 This frame 57 supports the bolt magazine 58 to which the bolts are fed from a hopper 59. The bolts are fed one by one from the hopper 59 to the magazine 58, and the threaded shanks of the bolts project out beyond the magazine as clearly shown in Fig. 1. In order to provide for the delivery of the bolts one by one into position for receiving the nuts, I provide the following mechanism:

30 A stop-member 60 is pivotally mounted at 61. A finger 62 on said stop-member projects through the slot 63 into the magazine to prevent the bolts in the magazine from dropping. This stop-member 60 has the 40 cam-face 64 which engages the spring-arm 65 with the inwardly projecting finger 66 adapted to enter the slot 63. A link 67 is pivotally connected to the stop-member 60, the lower end of the link being pivotally connected to the rocker 68 mounted on the rock shaft 69. The rocker 68 is provided with the ledge 70 to support the bolt 71. Secured to the rocker-shaft 69 is the arm 72 which arm is adapted to engage the pawl 73 45 pivoted at 74 to a bracket 75 on the stationary guide 55. As the frame 57 advances the arm 72 will pass under the pawl 73 and lift the same, but on the return stroke of the slide the arm will ride up on said pawl and rock the shaft 69, thereby moving the rocker 68 and releasing the bolt 71 from the ledge 70. Through the connection by the link 67 with the stop-member 60, said stop-member 50 will be moved to the position indicated in dotted lines Fig. 7, thereby releasing another bolt, and moving the spring finger 66 into position to temporarily retain the bolts above in the magazine.

The lever 22 is connected by the link 77 60 to the arm 79 on the slide 56 whereby when

the lever 22 is moved to advance the slide-block 19, the frame 57 will be moved toward the nut-holder, as clearly shown in Fig. 3. The spring 80 acts normally to hold the parts in position shown in Fig. 1.

70

I have illustrated my invention as a single machine, although it is apparent that the parts shown may be duplicated and the shaft 13 may be used to drive mechanism in duplicate.

75

When the machine is in operation, the nuts are fed to the nut-magazine and the bolts to the bolt-magazine one by one from the hoppers 34 and 59. With a nut in the position indicated in Fig. 1 and a bolt 71 in the position indicated in the same figure, power is applied, and, through the action of the cam 15, the slide-block 19 will be advanced, and through the connection of the lever 22 with the arm 79, the frame 57 will be simultaneously moved. The movement of the slide-block 19 advances the nut-carrier 26 carrying with it the pin member 27. The pin member 27 enters the opening in the nut and the nut is moved from the magazine, the 80 shutter 35 yielding to allow for the passage of said nut. The nut is advanced into the flaring mouth of the nut holder, and as stated above, if said nut is not in position to register properly with the square seat 49, 85 and should assume the position indicated in dotted lines Fig. 6, the corner of the nut riding over the corner of the cam-slot 48 will cause the nut to be moved to proper position to register with the seat 49, and further advance of the carrier 26 will seat the nut in the seat 49 and into contact with the end of the bolt. As the nut-holder is rotating with the sprocket, a rotary movement is imparted to the nut when in the squared 90 seat 49 which screws the nut onto the bolt. When the nut enters the seat, the pin 27 will be arrested in its forward movement by engagement of the transverse pin 28 stop 32, thus permitting the bolt to enter the bore 100 of the nut. The delay face 15^a on the cam 15 holds the carrier 26 and slide 57 from movement until the nut has been applied to the bolt whereupon said cam permits the backward movement of the arm 22 due to 105 the action of the spring 80 whereupon the carrier is withdrawn and at the same time the frame 57 moves backward carrying the bolt with the nut on it until the arm 72 rides up on the pawl 73, whereupon the bolt is released and drops to a suitable receptacle below, while another bolt is dropped from the magazine, the finger 66 of the spring arm 65 acting to retain the bolts above in position from dropping. The withdrawal of 110 the spindle 26 to its normal position, as indicated in Fig. 1, permits another nut to drop down into position to be picked up by the pin 27 upon the next advance of the spindle 26.

- In case, for any reason, the nut should fail to connect with the bolt due to an imperfection in the opening in the nut, to prevent injury to the machine and to provide for the withdrawal of any such imperfect nut so as not to interfere with the next operation, as stated above, the carrier 26 is preferably magnetized so that upon the withdrawal of said carrier in the case of an imperfect nut, 5 the nut will adhere to the carrier and will be drawn back into contact with the shutter which lies against the carrier when the carrier is advanced and the nut will be stripped therefrom.
- 10 15 What I claim is:
1. In a machine for applying nuts to bolts, the combination with a suitable frame, of a nut-carrier, means for advancing and withdrawing same, a nut-magazine in the path of movement of said carrier, a rotary nut-support beyond said magazine, means for rotating same whereby on the advance of said nut-carrier, said carrier enters the opening in a nut in said magazine and delivers same to said rotary holder, and a bolt-support movable to and from said nut-support. 20
  2. In a machine for applying nuts to bolts, the combination with a suitable frame, of a nut-carrier, means for advancing and withdrawing same, a nut-magazine in the path of said carrier, a rotary nut-holder, means for rotating same whereby said carrier enters the opening in a nut in said magazine and delivers same to said nut-holder, a bolt-holder movable to and from said nut-holder, and means for simultaneously advancing said nut-carrier and moving said bolt-holder in position to engage said nut. 30
  3. In a machine for applying nuts to bolts, the combination with a suitable frame, of a nut-carrier, means for advancing and withdrawing same, a yieldable pin-member extending beyond said nut-carrier, a nut-magazine in the path of said carrier, a rotary nut-holder, means for rotating same, whereby as said carrier advanced said pin-member enters the opening in a nut in said magazine and delivers same to said holder, and a bolt-holder movable to and from said nut-holder. 40
  4. In a machine for applying nuts to bolts, the combination with a suitable frame, of a nut-carrier, means for advancing and withdrawing same, a spring-actuated pin-member in said carrier projecting beyond same, a nut-magazine in the path of said carrier, a rotary nut-support, means for rotating same whereby as said carrier advances, said pin-member enters the opening in a nut in said magazine and delivers same to said nut-holder, and a bolt-support movable to and from said nut-holder. 50
  5. In a machine for applying nuts to bolts, the combination with a suitable frame, of a magnetized nut-carrier, means for advanc-
- ing and withdrawing same, a yieldable pin-member in said carrier projecting beyond the same, a nut-magazine in the path of said carrier, a rotary nut-holder, means for rotating same whereby on the advance of said carrier, the said pin-member enters an opening in a nut in said magazine and delivers same to said nut-holder, and a bolt support movable to and from said nut-holder. 70
6. In a machine for applying nuts to bolts, the combination with a suitable frame, of a nut-carrier, means for advancing and withdrawing same, a spring-actuated yieldable pin-member carried in said carrier extending beyond the same, a projection on said pin-member engaging a slot formed in said carrier, a stop in the path of said projection, a nut-magazine in the path of said carrier, a rotary nut-holder, means for rotating same whereby as said carrier is advanced, said pin-member enters the opening in a nut in said magazine and delivers same to said nut-holder, and a bolt-support movable to and from said nut-holder. 80
7. In a machine for applying nuts to bolts, the combination with a suitable frame, of a nut-carrier, means for advancing and withdrawing same, a nut-magazine in the path of said carrier, a shutter for the outlet of said magazine, a rotary nut-holder, means for rotating same whereby as said carrier is advanced, said pin-member passes through the opening in said magazine forcing open said shutter and delivering said nut to said rotary nut-holder, and a bolt-support movable to and from said nut-holder. 85
8. In a machine for applying nuts to bolts, the combination with a suitable frame, a nut-carrier, means for advancing and withdrawing same, a yieldable pin-member in said carrier extending beyond same, a nut-magazine in the path of said carrier, a spring-actuated shutter for the outlet of said magazine, a rotary nut-holder, means for rotating same whereby as said carrier is advanced, said pin-member passes through the opening in a nut in said magazine forcing open said spring-actuated shutter and delivering said nut to said rotary nut-holder, and a bolt-support movable to and from said nut-holder. 90
9. In a machine for applying nuts to bolts, the combination with a suitable frame, of a guide, a sliding block in said guide, a rotary cam engaging said block, a nut-carrier connected to said block, a yieldable pin-member in said nut-carrier projecting beyond the same, a nut-magazine in the path of said carrier, a rotary nut-holder, means for rotating same whereby as said carrier advances, said pin-member enters an opening in a nut in said magazine and delivers same to said holder, and a bolt-support movable to and from said nut support. 100
10. A machine for applying nuts to bolts, 130

the combination of a rotary nut holder having an angular seat, means for rotating same, said nut-holder having tapering faces at its entrance and a cam-face on the upper face 5 of said opening, and means for introducing a nut to said holder whereby if said nut is introduced to said holder with its sides out of register with the corresponding sides of

said seat, the said cam will position said nut to enter said seat.

In testimony whereof, I, the said HANSON THOMAS, have hereunto set my hand.

HANSON THOMAS.
